DEVICE FOR SUPPORTING WINDOW SHADES

Robert W. Hagel, New Orleans, La., assignor of
one-half to August W. Nolde, New Orleans,
La.

Application October 12, 1932. Serial No. 637,500

3 Claims. (Cl. 156—27)

This invention relates to a device for supporting window shades at various vertical heights along the window frame.

An object of the invention is the provision of a device which not only supports a window shade across a window frame but is adapted to move the shade at various heights along the frame.

A further object of the invention is the provision of a support for window shades, the support including a carriage having adjustable means for supporting a window shade across a window with means for moving the shade to various horizontal positions so that the shade may be positioned where the direct rays of the sun-light pass through the window.

This invention will be best understood from a consideration of the following detailed description, in view of the accompanying drawing forming a part of the specification; nevertheless, it is to be understood that the invention is not confined to the disclosure, being susceptible of such changes and modifications which shall define no material departure from the salient features of the invention as expressed in the appended claims.

In the drawing:

Figure 1 is a view in elevation of the window shade supporting device constructed in accordance with the principles of my invention.

Figure 2 is a horizontal section taken along the line 2—2 of Figure 1.

Figure 3 is a transverse vertical section taken along the line 3—3 of Figure 1.

Figure 4 is a view in perspective of the plate for securing the ends of the supporting cable together.

Figure 5 is a fragmentary end view of the carrying plate for the window shade.

Figure 6 is a view in perspective of a carriage which is movable to various positions along the vertical support.

Figure 7 is a fragmentary view in perspective of a channel member which is adapted to adjustably mount the window shade supports,

Figure 8 is a fragmentary view in perspective of one of the window shade supports, and

Figure 9 shows a modified form of a carriage and supporting plate for the window shade.

Referring more particularly to the drawing, 10 designates one member of a window frame and upon this member is secured at 11 a channel member 12. This channel member extends vertically of the frame.

The channel member has a base portion 13 which is provided with perforations for secu-

ring this channel member, as shown at 11, to the frame. The channel member includes side flanges 14 and lateral extensions 15.

A grooved pulley 16 is secured to the frame at the upper end of the channel member 12 while 60 a grooved pulley 17 is secured to the member 10 of the window frame at the bottom of the channel member. A cable 18 is trained on the pulleys 16 and 17. The cable consists of a single strand of material and has one of its free ends 20 threaded through openings 21, 22 and 23 in a metal plate 24. The other free end 25 of the cable is threaded through openings 26, 27 and 28. A portion of the cable, as shown at 29, is looped around a neck or reduced portion 70 which connects a head 30 to the plate 24 in order to further aid in holding the ends of the cable in position. By means of the plate 24 and the perforations, the ends are connected together to form an endless cable and the plate further 75 provides means for drawing the cable taut when any looseness appears in the same.

A carriage 35 is provided with inturned flanges embracing flanges 15 of the support or channel member 12 so that the carriage will be slidably mounted on the member 12.

A plate 37 is secured to the carriage 35 and projects laterally therefrom and is provided with perforations 38 through which the cable 18 is threaded. In other words, the plate 37 with its 80 perforations provides means for securing the cable to the carriage 35.

A supporting plate or extension 40 is secured to the outer face of the carriage 35 and projects laterally therefrom and across the opening in 90 the frame of the window. The plate is cut away at 41, 42 in order to reduce the weight of the same but leaving sufficient metal for rigidly supporting the curtain.

An angularly-shaped member 45 is secured to the outer face of the plate 40 and is provided with inturned flanges 46 and 47 at its free edges to provide a channel member to receive the angle bars 48 and 49. The angle bar 48 is provided with a lip 50 having a perforation 51 to receive the pintle on the end of a curtain rod.

The angle iron 49 is provided with a lip 52 which has an inclined slot 53 opening into a horizontal slot 54 which receives the flat end of a shaft 105 which is controlled by the usual ratchet members and spring of the curtain. The angle irons 48 and 49 fit neatly within the angle member 45 and these members may be moved outwardly or inwardly of the member 45 in order to ad- 110

just the members 48 and 49 to the proper position for supporting curtains of various widths.

In Fig. 9 is shown a modified form of the carriage 35^a and the supporting plate 40^a is bent 5 at an angle of approximately 45° to provide an extension 60. This type is used where the windows are set inwardly of the wall and the jambs are inclined at an angle. In other words, the carriage 35^a is identical in all respects with the 10 carriage 35 but the plate 40^a is bent to form an extension 60 at whatever angle will be desirable for maintaining the curtain directly across the window.

The operation of my device is as follows: With 15 the parts shown in position in Fig. 1, the cable is moved for moving the carriage 35 to the position desired for supporting a curtain at the proper height. The cable is made sufficiently taut in order to prevent the carriage 35 from 20 moving downwardly after it has been positioned. The angle irons 48 and 49 are moved in proper position to receive the fixtures of the curtain rod and the curtain is in position to be elevated or lowered not only on its own rod, but the curtain per se may be removed bodily upwardly and 25 downwardly of the window frame.

I claim:

1. A device for supporting curtains comprising 30 a channel member adapted to be secured to a

window frame, a carriage slidably mounted in the channel member, means for retaining the carriage at various vertical positions and for moving the carriage vertically of the channel member, a horizontal channel member secured to the carriage and means adjustable lengthwise in the horizontal channel member for supporting curtains of varying widths. 80

2. A device for supporting curtains comprising 85 a guiding support, a carriage slidably mounted for vertical movement on the support, a channel member secured to the carriage and disposed in a horizontal plane, angle irons slidably mounted in the channel member and provided with means for supporting a curtain, and means for moving the carriage vertically along the support. 90

3. A device for supporting curtains comprising 95 a guiding support, a carriage slidably mounted for vertical movement on the support, a channel member secured to the carriage and disposed in a horizontal plane, the channel member being L-shaped and having turned flanges along the edges thereof, L-shaped angle irons slidably mounted in the channel member, each angle iron having a laterally disposed lip provided with 100 means to support the curtain, and means for moving the carriage vertically along the support. 105
